Patented Mar. 26, 1968

210,604

HOLDER FOR FIREWOOD CARRIER

Herbert R. Sanders, 12436 Elaine Drive,

Des Peres, Mo. 63131

Filed Apr. 12, 1967, Ser. No. 6,654

Term of patent 14 years

(Cl. D33—3)

FIG. 1.

FIG. 2.

FIG. 4.

FIG. 3.

FIG. 1 is a top plan view of a holder for a firewood carrier embodying my new design;

FIG. 2 is a front elevation of the holder of FIG. 1;

FIG. 3 is a side elevation, as viewed from either side, of the holder of FIG. 1;

FIG. 4 is a rear elevation of the holder of FIG. 1.

I claim:

The ornamental design for a holder for a firewood carrier, substantially as shown.
